Primary Examiner—Antoine Duval Davis*Attorney, Agent, or Firm*—Stetina Brunda & Buyan[57] **CLAIM**

The ornamental design for a timing light for automotive engines, as shown and described.

DESCRIPTION

FIG. 1 is a top perspective view of the timing light for automotive engines showing our new design;

FIG. 2 is a side view thereof the opposite side being a mirror image;

FIG. 3 is a bottom view thereof;

FIG. 4 is a rear end view thereof; and,

FIG. 5 is a front end view thereof.
